UNITED STATES PATENT OFFICE.

ROSWELL S. JUDSON AND CHARLES M. ACKERMAN, OF MATTEAWAN, N. Y.

MACHINE FOR FELTING AND SIZING HATS AND OTHER FABRICS.

SPECIFICATION forming part of Letters Patent No. 296,415, dated April 8, 1884.

Application filed January 19, 1884. (No model.)

To all whom it may concern:

Be it known that we, ROSWELL S. JUDSON and CHARLES M. ACKERMAN, citizens of the United States, residing at Matteawan, in the 5 county of Dutchess and State of New York, have invented certain new and useful Improvements in Machines for Felting and Sizing Hats and other Fabrics; and we do declare the following to be a full, clear, and exact description of the invention, such as will enable others skilled in the art to which it appertains to make and use the same, reference being had to the accompanying drawings, and to the letters and figures of reference marked 15 thereon, which form a part of this specification.

Our invention relates to improvements in machines used in the manufacture of hats, and has for its object to provide an efficient and 20 easily-operated machine for use in the operation of sizing fur-hats; and it consists in the construction, combination, and arrangement of the several parts, as will be hereinafter fully described and claimed.

25 In the drawings, Figure 1 is a side elevation, Fig. 2 is a plan view, Fig. 3 is a vertical longitudinal section, of our machine. Fig. 4 is a detail view of the swinging bearing or lever-support; and Fig. 5 is a detached cross-section of the bed enlarged on about line x x , Fig. 2.

The box or tub A is supported on legs A' A², as shown. The ends B B' of the box are inclined inwardly from their upper edges, and 35 the side-boards, B² B², are projected at their lower sides forward beyond the end board, B, and serve as a support for the bar C. This bar C has a central opening midway its ends. The adjusting-screw D turns through this 40 opening, and is provided on its upper end with a button or head, D', whereby it may be turned.

A table, E, is secured on the end B of the tub. This table is inclined downward toward 45 the tub, and is provided with cleats E' on its opposite edges. These cleats serve to prevent the water or other wash from flowing onto the floor when the hat-stocks are placed on said table, after being dipped in the tub. The bed 50 F is mounted on the tub about midway its ends, and extends the full width thereof, its

outer ends being flush with the outer sides of the tub, as most clearly shown in Fig. 2. The bed is provided on its upper face with a series of longitudinal corrugations. The rubber G is also provided with corrugations, and has flanges G' depending from its opposite sides, which, when the rubber is rested against the bed, project down on opposite sides of the latter. Eyes H H are projected laterally 60 from the rubber, and slide on rod or rail, presently described. These eyes are preferably the ends of cross-bars H', which are secured on the upper side of the rubber, as clearly shown. A bar, I, is secured at one end to the 65 rubber, and extends rearwardly therefrom, and its other end is bifurcated and rests on opposite sides of the lever J. This lever is pivoted at its lower end on a bar, J', and is provided near its upper end with a slot, J². 70 The bar I is secured to the lever by a pin, I', passed through this slot J². By this construction it will be seen that the outer end of bar I, where it joins the lever, may be moved vertically as the rubber is moved up and 75 down in the manner presently described. It will also be seen that this enables the movement of the rubber in a horizontal plane by the lever swinging in an arc, as shown. Vertical guides K K are secured in the outer sides of 80 the tub in line midway the ends of the corrugated bed F. The standards L are secured and movable vertically in these guides, as indicated in Fig. 1. Bars M are secured midway their ends on the upper end of the standard. These 85 bars extend horizontally on opposite sides of the standard to a point beyond the opposite ends of the bed F. Short standards N are bent or otherwise projected upward from the opposite ends of the bar M and support the rods 90 or rails O. The eyes H of the rubber are secured and move on this rail, as clearly shown. In the lower end of the standard L, I form a series of holes, L'. The treadle P is composed of two pivoted side bars, P' Q, and a tread-bar, 95 P². It also has a cross-bar, P³, which is engaged by the adjusting-screw D in the operation of the machine. The side bars, P, are pivoted to the lower end of the bracket Q, preferably in the slot Q', and their inner ends are secured to 100 the lower end of standards L by pins passed through either of holes L' desired. The brack-

ets Q are pivoted at their upper ends to the outer sides of legs A'.

In operation it is understood the tub is filled with boiling water, and the hats are dipped 5 therein, and then placed between the bed and rubber, and the latter is worked back and forth until the operation is completed. By our arrangement of the rubber-supporting devices it will be seen they are entirely without the tub. 10 This is desirable, as it renders them free from contact with the water or other liquid used, and also does not take up any room in the tub and enables the use of a bed the full width of the tub, as will be seen. By means of the treadle 15 the rubber may be adjusted to any suitable distance from the bed. The movement of the standards L is in a vertical line, and the treadle works in an arc.

In order to permit the smooth operation of 20 the parts, we pivot the bearing-brackets so it will swing as indicated in dotted lines, Fig. 1, and permit the end of the treadle to move vertically with the standard.

It is obvious that the rod or rail might be 25 supported on the upper end of the standard in various ways; but we prefer that shown, as it is simple and can be easily constructed.

The set-screw D may be adjusted to limit the 30 upward movement of the treadle, and consequently the downward movement of the rubber, as will be seen.

The grooves F', it will be seen, terminate at 35 a point near the sides of the bed, and that holes F² are formed through the latter, leading from the middle of said grooves down into the tub. This forms the bed slightly concave, and prevents water passing off the edges of same onto 40 the floor. It also permits the water to flow back into the tub, and has a tendency to keep the hats in the middle of the bed, as will be understood.

Having thus described our invention, what 45 we claim, and desire to secure by Letters Patent, is—

1. In a hat-sizing machine, the combination of the tub, the corrugated bed mounted thereon, the guides secured on the outer sides of said tub, the standards L, secured and movable vertically in said guides, the rubber having lateral

eyes, the rods or rails passed through said eyes 50 and supported on standards L, and suitable operating mechanism, substantially as and for the purposes set forth.

2. In a sizing or felting machine, the combination of the tub having a corrugated or roughened bed, and provided with guides K on its outer sides, the standards secured and movable vertically in said guides, and provided on the upper end with a horizontal rod, the rubber supported on said rod and movable, as described, 60 the brackets O, pivoted at their upper ends, and the treadles pivoted to the lower ends of said brackets, and connected with standards L, substantially as set forth.

3. The combination of the tub, the corrugated bed, the vertically-adjustable rubber support, the rubber, the rod, having one end secured rigidly to the rubber and extended therefrom, the lever J, pivoted at its lower end, and provided near its upper end with a slot, 70 J², and a pin passed from the rod I into or through said slot, substantially as set forth.

4. The hat-sizing machine herein described, composed of the tub provided with a table and a corrugated rubber, as described, and having 75 guides K secured on its outer sides, the standards L, the rods O, mounted thereon, the rubber provided with eyes sliding on said rods, the bar I, extended from said rubber, the lever J, pivoted at its lower end, and provided near 80 its upper end with slots J², wherein the bar I is connected, the brackets Q, pivoted at their upper ends, and the treadle pivoted to the lower ends of the brackets and connected with the standards L, substantially as set forth. 85

5. In a sizing-machine, the bed F, having grooves formed in its upper face and terminating at a point near the sides thereof, and provided with vertical openings formed through it from the center of the grooves, substantially 90 as and for the purposes set forth.

In testimony whereof we affix our signatures in presence of two witnesses.

ROSWELL S. JUDSON.
CHARLES M. ACKERMAN.
